UNITED STATES PATENT OFFICE.

WALTER SCOTT, OF PLAINFIELD, NEW JERSEY.

PRINTING-PRESS.

SPECIFICATION forming part of Letters Patent No. 758,112, dated April 26, 1904.

Application filed February 11, 1901. Serial No. 46,924. (No model.)

To all whom it may concern:

Be it known that I, WALTER SCOTT, a citizen of the United States, and a resident of Plainfield, in the county of Union and State of New Jersey, have invented certain new and useful Improvements in Printing-Presses, of which the following is a specification.

My invention relates generally to printing-machines, and more particularly to the inking or other fluid-distributing apparatus on same, and to other improvements and features of construction or arrangement, which will hereinafter be more particularly described.

My invention is embodied in the machine shown in the accompanying drawings, which illustrate a rotary printing-press constructed with a plate-cylinder for carrying forms of any suitable material. In machines of this character it is important to have the form-inking rolls placed very closely together, so as to take up as little room as possible around the surface of the plate-cylinder. To this end I construct the plate-cylinder with the usual large gear, corresponding in size to the said cylinder, and also with a gear of a diameter somewhat smaller than the pitch-line of the said plate-cylinder and the main gear. By this means I am enabled to place the intermediate gears, transferring motion from the plate-cylinder through the usual steel rollers to the form-inking rollers, below the axial line between each two form-rolls, so that the gears will clear the shanks of the rolls and leave room for adjustment, thereby accomplishing my object, the train of gears being, further, so constructed as to drive the form-inking rolls at the same surface speed as the surface speed of the form on the plate-cylinder. I further construct the shaft of the plate-cylinder with a cam provided with a groove in which the rollers of two rock shafts or levers rest. These shafts or levers are provided with rollers at their other ends, which engage with spools on the ends of the steel rollers that drive the form-inking rolls, thus vibrating the said rolls in an endwise direction; but the elements are so constructed and arranged that a movement in one direction only takes place while the inking-rolls are in contact with the form and continues until the inking-rolls pass

off the form, the vibratory return movement taking place after the said inking-rolls have passed entirely off the form, thus preventing any destruction or wear of the design on the form. Above the form inking and distributing device is placed an ink-distributing cylinder supplied with ink from the fountain-roll by means of a ductor-roll mounted on a rock-shaft. The ductor-roll is operated by means of a cam-and-lever movement, which is adjustable so as to regulate the length of time it remains in contact with the fountain-roll. The ink-distributing cylinder, which is fed by the ductor-roll, is driven by means of a gear meshing with the main gearing on the plate-cylinder, while it is vibrated by means of a rotating cam driven from a small gear attached to its shaft, which cam is vibrated by means of a stationary roller on the framework and has provided, as has also the shaft of the said cylinder, flanges or grooves which extend into each other, and this causes the cam and the cylinder to be vibrated in unison. In addition by this construction the number of vibrations given the distributing-cylinder will be less than the number of its revolutions, the proportion being variable by varying the size of the operating-gears in relation to each other. I further construct the plate-cylinder with an additional set of form-rolls for the following purpose: When printing in relief or otherwise, and especially when the paper has a surface which flakes by coming in contact with the plate or form, parts of the said surface of the paper sometimes adhere to the printing-plate and are transferred to the form-inking rolls, so that they become coated with fiber or dust from the paper and are not so effective in putting the ink on the form. By having them divided into two sets or by providing an additional set the form-inking rolls proper will be greatly relieved from such accumulation of fiber and will thereby do their work more effectively than if the dust or fiber is allowed to accumulate on the said rolls. Moreover, the additional set of rolls can be cleaned at intervals to remove the accumulation and could be supplied from their fountain-roll by some other fluid, such as oil, to keep the rolls moist and take up the dust, or

they could be supplied with a luminous ink before the other ink is put on, or they might be used to supply a differently-colored ink; but as part of the surface of the plate-cylinder is not occupied by the form the remaining surface is usually utilized as an ink-distributing surface, and it is therefore necessary that the additional set of rolls must be kept out of contact with this inking-surface on the plate-cylinder. This is done automatically by means of a cam movement, or it may be done by hand, as more fully hereinafter described, and in this way prevents these rolls which have an accumulation of paper fiber 10 from coming in contact with the inking-surface, thereby preventing the transference of the said paper fiber or dust to the form-inking rolls proper.

Proceeding now to the more detailed description, I have embodied the invention in the construction shown in the accompanying drawings, which structure may of course be varied at will in the minor details to meet various contingencies.

25 Figure 1 is a side elevation of the plate-cylinder of a rotary printing-press with adjacent means embodying my invention. Fig. 1^a is a detached view of the ductor-roll and adjacent elements. Fig. 2 is an end view of Fig. 3. Fig. 3 is a plan view. Fig. 4 is a sectional view of the cylinder and rolls, taken on the line *xx* of Fig. 2. Fig. 5 is a detail plan view of parts located on one side of the framework for varying the length of the dwell of the 35 ductor-roll. Fig. 6 is a side view in detail, showing one position of the ductor-roll. Fig. 7 is another detail view like Fig. 6, but showing the parts in a different position. Fig. 8 is an end view looking in the direction of the 40 arrow on Fig. 7.

In several instances parts have been omitted and broken away to illustrate the invention more clearly; but similar letters of reference indicate corresponding parts in the different 45 views.

I shall describe a rotary printing-press, and especially the inking mechanism of same, and afterward point out the novel features in the claims.

50 Mounted in a framework C of a suitable construction are the impression-cylinder A and the plate-cylinder B in such a position as to take an impression on the sheets of paper as they are fed between them. On the 55 upper side of the plate-cylinder are placed the form-inking rolls *f'*, which supply ink to the form. These rolls are in contact with and driven by the steel rolls *b'*, which are driven by the gears *e'*, mounted on the ends of their 60 shafts, which in turn mesh with the intermediate gears *d'*, mounted below the axial line of and between the form-rolls *f'* and which receive their motion from the gear *c'*, mounted on the plate-cylinder and of a diameter some-

what smaller than the pitch-line of the said 65 plate-cylinder. By this means the spaces occupied by the form-inking rolls *f'* are nearer together, which is of considerable advantage. In order, however, to compensate for the difference in surface speed between the plate-cylinder and the gear *c'*, carried by same, the gears *e'* on the ends of the rolls *b'* are made correspondingly smaller than the diameter of the latter, so that the form-inking rolls *f'*, driven by contact by the rolls *b'*, will have 70 their surfaces running at the same surface speed as the surface speed of the form on the cylinder B.

On the end of the shaft B' of the cylinder B is placed a side cam *g'*, provided with an 80 annular groove *g'*. Mounted in the vertically-slanting bushings *h* are the rock shafts or levers *h'*, provided at their lower ends each with an arm *h''*, carrying a roll *h'''*, and at their upper ends each with two arms *i'*. The rock-shaft *h* is caused to turn back and forth by the roll *h'''*, traveling in the groove *g'*, imparting a vibratory motion in an endwise direction to the steel rolls *b'* and the form-rolls *f'* through the instrumentality of the arms *i'*, 90 extending into the spools *j'* on the ends of the rolls *b'*. The construction and relative arrangement of the cam *g'* and the arms *i'*, however, is such that the vibration or endwise motion of the rolls will not change in its 95 direction while the form-rolls are on the form, thus preventing any wear or destruction of the design.

Mounted in the frame C, by means of two studs K, are two semicircular arms K', one on 100 each side of the machine. These arms have friction-rolls K⁵ at their lower ends, which come in contact with the two cams K², which are fastened on the rock-shaft K³, which latter is operated by the hand-lever K⁴. The 105 arms K' have raised portions K⁶, which almost contact with the shanks on the form-rolls *f'*, the distance being varied, so that as the arms are raised from their normal position they will raise the form-rolls away from 110 the form-cylinder in a radial direction, so that the rollers will be about equidistant from the form on the cylinder, and thus prevent the gears *e'* on the rolls *b'* from coming out of mesh with the gears *d'*, so that the rolls can 115 be inked up before inking the form.

In the framework above the form inking and distributing apparatus is placed an ink-distributing cylinder *b*, provided with distributing-rolls *b'* on its upper side. Cylinder *b* is supplied with ink by the ductor-roll *l*, which receives its supply from the ink-fountain roll *a*. This fountain-roll *a* is mounted in a convenient place near the cylinder *b* and is driven at a slow uniform speed by means 120 of the gears *c*, *d*, *e*, and *f*. The ductor-roll *l* is carried by two arms *l'*, one on each side 125 of the press, which are fixed on the rock-shaft

b^2 . On this rock-shaft b^2 is also fastened an arm n , terminating in a surface having a sharp edge t , which carries on one side the friction-roll n' , which is held up against the 5 cam m on the shaft of the fountain-roll a by means of a spring o' , (shown in Fig. 3,) fastened to the lever o of the rock-shaft b^2 and to the framework; the revolution of the cam m moving the ductor-roll l between the fountain-roll a and the distributing-cylinder b . The length of time of dwell of the ductor-roll against the fountain-roll is regulated in the following manner: On the end of the shaft of the fountain-roll a and immediately adjacent to the cam m is an eccentric cam p . Above the fountain upon the upright c' is placed a stud c^2 , which carries two levers q and r . The lever q is in contact with the eccentric cam p , and the lever r comes in contact with the surface t on the arm n . On the lever r is placed an adjusting-screw s , the point of which bears on a projection s' , which forms part of the lever q and which continuously rests upon the eccentric cam p . The 25 roll n' , being held continuously up against the cam m by the spring o' , follows the surface of same as it rotates, thereby rocking the shaft b^2 , and consequently the ductor-roll l . If this means alone were used, the motion 30 of the ductor-roll would always be the same and it would always remain a certain length of time in contact with the fountain-roll, thus transferring a constant amount of ink. As this is not desirable, the lever r and surface 35 or stop t are provided, which by their coöperation prevent the ductor-roll from remaining the full length of time allowed by the cam m in contact with the fountain-roll. This is accomplished by the cam p lifting the 40 levers q and r up, thus bringing the latter into contact with the surface t , and by adjusting the screw s the lever r is moved up or down with relation to the lever q , so that it will encounter the stop t sooner or later or 45 not at all, as the case may be. By this means the ductor-roll may remain in contact with the fountain-roll a very short period of time or the full length of time allowed by the cam m , according to the adjustment of the lever r 50 with relation to the surface or stop t , and in that way transfer more or less ink to the distributing-cylinder b , from whence the ink is transferred to the distributing and form-inking rolls by means of two rollers d^2 , placed on 55 each side of the extension of the framework.

The rotating cam p , shown on the shaft of the fountain-roll, may be mounted on another shaft or stud instead.

A vibrating motion is imparted to the cylinder b in the following manner: On the framework C between the cylinders B and b is placed a stud f^2 . This stud carries a gear V , which meshes with the gear u on the cylinder B and with the gear u' on the cylinder b . On the

opposite side of the press in the framework C , between the cylinders B and b , is placed a stud e^2 , on which is mounted a rotating cam w , admitting of endwise movement, having a gear y thereon, which is driven by the small gear x on the end of the shaft of cylinder b . 70 On the frame C is bolted a stationary bracket z , carrying the roll z' , which runs in the groove w' of the cam w , whereby the cam is vibrated on the stud e^2 as it revolves. On the end of the cam w are placed two circular tongues a' , 75 forming a groove a^2 , which coacts with the similarly-formed tongues and groove on the shaft of the cylinder b , thus causing the cylinder b to vibrate endwise in unity with the rotation of the cam w , the number of vibrations of the cylinder b being, however, less than the number of its revolutions and may be varied by changing the proportions of the gears x and y . 80

On the lower side of the cylinder B are placed an additional set of rolls, consisting in this instance of three rolls S , similar in construction to the form-rolls f' , which receive their supply of ink from the fountain D in a similar manner as the upper set of rolls. 90 These form-rolls are mounted on the arms E , fastened to the rock-shafts F . On one of these rock-shafts F is mounted a gear G , which connects with the gear u on the cylinder B . This gear G in turn drives the gears H , which in turn drive the polished rolls S' , which come in contact with and drive the form-rolls S . These steel rolls S' are caused to vibrate by the cam g' in the same manner and by the same mechanism as the rolls on the upper side 100 of the cylinder B .

On the frame C below the arms E is placed a rock-shaft I , on which are mounted two arms I' . On the end of these arms are placed a second set of arms I^2 , which carry on their ends 105 friction-rolls I^3 , coming in contact with the arms E . The second set of arms I^2 are adjustable by adjusting-screws I^3 , so as to raise and lower the arms E to bring the form-rollers into proper relation with the cylinder B . 110 It will be seen that by raising the lever I^4 the arms E will be lowered, bringing the form-rolls out of contact with the form. This operation is also performed automatically by the lever I^5 and its friction-roll I^4 , coming in contact with the cam J on the shaft of the plate-cylinder, which is so adjusted that the form-rolls do not contact with the portion of the cylinder utilized as an ink-distributing surface. As the arms E swing from the center 115 of the gear G it will be seen that the gearing is always in mesh and that the ink or other fluid will be distributed even while the rolls are not in contact with the form on the cylinder and that these rolls can be raised and 120 lowered at any time desired during the rotation of the cylinder B .

Having thus described my invention, what

I claim as new, and desire to secure by Letters Patent of the United States, is—

1. In a printing-press, the combination of a plate-cylinder, a plurality of form-inking rolls arranged circumferentially of the same, a plurality of superposed rolls driving the form-inking rolls by contact, a circumferential gear carried by the plate-cylinder of a diameter somewhat less than the pitch-line of the said cylinder, a plurality of intermediate gears mounted below the axial line of the form-inking rolls and driven by the said circumferential gear at a slower surface speed than the plate-cylinder, a gear, mounted on the end of each of the superposed rolls, of a smaller diameter than the diameter of the said superposed rolls, meshing with the intermediate gears aforesaid and driving the superposed rolls and through them the form-inking rolls at the same surface speed as the plate-cylinder, substantially as described.
2. In a printing-press, the combination of a plate-cylinder, a plurality of form-inking rolls arranged circumferentially of same, a plurality of superposed rolls driving the form-inking rolls by contact, a circumferential motion-transmission means carried within the pitch-line on the plate-cylinder, means for co-acting therewith mounted below the axial line of the form-inking rolls and extending inside of the pitch-line of the said cylinder, and means, mounted on the ends of the superposed rolls, of a less diameter than the diameter of the said superposed rolls, for receiving motion from the coacting means, substantially as described.
3. In a printing-press, the combination of a plate-cylinder adapted to carry a form or plate from which impressions are to be made, a plurality of form-inking rolls arranged circumferentially of the cylinder, a plurality of superposed and lengthwise-vibrating rolls driving said form-inking rolls by contact, and means for moving the rolls lengthwise in one direction only while the form-inking rolls contact with the form, substantially as described.
4. In a printing-press, the combination of a plate-cylinder adapted to carry a plate or form from which impressions are to be made, a plurality of form-inking rolls arranged circumferentially of the cylinder, a plurality of superposed and lengthwise-vibrating rolls driving said form-inking rolls by contact, a cam carried on the shaft of the plate-cylinder, a shaft mounted in the framework, a roller carried on the end of said shaft adapted to cooperate with the cam on the shaft of the plate-cylinder, two arms carried by the said shaft at its other end and at right angles to its axis, spools carried by the rolls aforesaid, and means carried by the arms of the shaft for cooperating with the spools to vibrate the rolls, the movement being in one direction only

while the form-inking rolls contact with the form, substantially as described.

5. In a printing-press, the combination of a rock-shaft carrying a ductor-roll, an arm carried by said rock-shaft terminating in a contacting portion, a lever pivoted at one end, a second lever also pivoted at one end and resting on a portion of the first-mentioned lever and terminating in a portion adapted to contact with the contacting portion of the arm on the rock-shaft, and means for regulating the distance of the two contacting portions with relation to each other by regulating the relative position of the levers, substantially as described.

6. In a printing-press, the combination of a rock-shaft carrying a ductor-roll, an arm carried by said rock-shaft terminating in a contacting portion, a fountain-roll having a rotary motion, a lever pivoted at one end, a second lever also pivoted at one end and resting on a portion of the first-mentioned lever and terminating in a portion adapted to contact the contacting portion of the arm on the rock-shaft, and means operated by the rotation of the fountain-roll whereby the two contacting portions are kept in contact at predetermined intervals, substantially as described.

7. In a printing-press, the combination of a rock-shaft carrying a ductor-roll, an arm carried by said rock-shaft terminating in a contacting portion, a fountain-roll, having a rotary motion, a lever pivoted at one end, a second lever also pivoted at one end and resting on a portion of the first-mentioned lever and terminating in a portion adapted to contact the contacting arm of the rock-shaft, means operated by the rotation of the fountain-roll whereby the two contacting portions are kept in contact at predetermined intervals, and adjustable means also operated by the rotation of the fountain-roll whereby the period or length of time of contact is regulated, substantially as described.

8. In a printing-press, the combination of a fountain-roll, means for rotating the fountain-roll, a rock-shaft carrying a ductor-roll, an arm carried by the rock-shaft terminating in a contacting portion, a friction-roller carried by the said arm, a cam on the shaft of the fountain-roll adapted to coact with the friction-roller so as to rock the rock-shaft carrying the ductor-roll, a second cam carried by the shaft of the fountain-roll, a pivoted lever adapted to rest with its free end on the second cam, a second pivoted lever adapted to rest on a portion of the first lever and terminating in a portion adapted to contact the contacting portion on the arm of the rock-shaft thereby regulating the period or length of time of contact or dwell of the ductor-roll against the fountain-roll, and cooperative means formed between the two levers whereby the relative

position of the second lever with regard to the arm on the rock-shaft with which it contacts may be varied, substantially as described.

- 5 9. In a printing-press, the combination of an ink-distributing cylinder slidably mounted adjacent to the form-inking rolls and adapted to supply the latter with ink, means for imparting a predetermined number of revolutions to the cylinder in a given space of time, means for imparting a less, but variably-pre-determined, number of endwise vibrations to the cylinder in the same space of time, and means for varying the number of vibrations 10 of the cylinder relative to the number of revolutions, substantially as described.

- 10 10. In a printing-press, the combination of an ink-distributing cylinder, slidably mounted adjacent to the form-inking rolls and adapted 20 to supply the latter with ink, means for imparting a predetermined number of revolutions to the cylinder in a given space of time, means for imparting a less, but variably-pre-determined, number of endwise vibrations to 25 the cylinder in the same space of time, and means for varying the number of vibrations of the cylinder relative to the number of revolutions, comprising a rotatable cam slidably mounted on a stud in the framework, a gear 30 carried by said cam, a gear carried on the shaft of the cylinder meshing therewith and rotating the cam, a stationary friction-roller mounted in the framework adapted to coact with the cam to vibrate the same as it revolves, 35 and co-operative means formed between the cam and the cylinder whereby the vibration of the cam is imparted to the cylinder, substantially as described.

11. In a printing-press, the combination of 40 an ink-distributing cylinder slidably mounted adjacent to the form-inking rolls and adapted to supply the latter with ink, means for rotating the cylinder, a rotatable cam slidably mounted, means for rotating the cam from 45 the cylinder, means whereby the rotation of the cam causes its vibration, and means for imparting the vibrations of the cam to the cylinder, substantially as described.

12. In a printing-press, the combination of 50 a plate-cylinder, an ink-distributing surface on said cylinder, a set of form-inking rolls adapted to contact the form carried by said cylinder and adapted also to contact the ink-distributing surface, and an additional set of 55 form-inking rolls adapted to contact the form after each impression prior to its contact with the first-mentioned set of inking-rolls, and adapted further not to contact the ink-distributing surface on the cylinder, substantially 60 as described.

13. In a printing-press, the combination of 65 a plate-cylinder, an ink-distributing surface on said cylinder, a set of form-inking rolls adapted to contact the form carried on the

cylinder and adapted also to contact the ink-distributing surface, and means for contacting the form on the cylinder after each impression and prior to its contact with the form-inking rolls for the purpose of removing the paper fiber or dust on said form, and adapted 70 further not to contact the ink-distributing surface on the cylinder so as not to transfer the said dust or fiber to the form-inking rolls substantially as described.

14. In a printing-press, the combination of 75 a plate-cylinder, a circumferential gear carried by the cylinder, a cam mounted on the shaft of the said cylinder, a pair of arms pivoted on a rock-shaft, a plurality of form and distributing rolls carried by said arms, a train 80 of gears driving the distributing-rolls contacting with the form-rolls, an intermediate gear on the rock-shaft in constant mesh with the circumferential gear on the cylinder and the train of gears driving the distributing-rolls, a second rock-shaft mounted below the arms pivoted to the first rock-shaft, a pair of arms carrying a friction-roll pivoted to two 85 arms on the second rock-shaft, and a lever mounted on the second rock-shaft carrying a 90 friction-roll coöperating with the cam on the shaft of the cylinder, for the purposes as set forth, substantially as described.

15. In a printing-press, the combination of 95 a rock-shaft carrying a ductor-roll, an arm carried by said rock-shaft terminating in a contacting portion, a lever pivoted at one end, a second lever also pivoted at one end and resting on a portion of the first-mentioned lever and terminating in a portion adapted to 100 contact the contacting portion of the arm on the rock-shaft, and means whereby the two contacting portions are kept in contact at predetermined intervals, substantially as described. 105

16. In a printing-press, the combination of 110 a rock-shaft carrying a ductor-roll, an arm carried by said rock-shaft terminating in a contacting portion, a lever pivoted at one end, a second lever also pivoted at one end and resting on a portion of the first-mentioned lever and terminating in a portion adapted to 115 contact the contacting arm of the rock-shaft, means whereby the two contacting portions are kept in contact at predetermined intervals, and adjustable means whereby the period or length of time of contact is regulated, substantially as described.

17. In a printing-press, the combination of 120 a distributing-cylinder, a fountain whose roll has a rotary motion, a ductor-roll mounted on arms on a rock-shaft and caused to vibrate in contact with the distributing-cylinder and the fountain-roll, an arm on the rock-shaft whose end terminates in a contacting portion, a lever pivoted at one end and contacting with a 125 rotating cam, a second lever pivoted at one end the other end contacting with the contact-

ing portion of the arm on the rock-shaft, and an adjusting means for regulating the distance between the two arms whereby the time of contact between the fountain-roll and the 5 ductor-roll can be regulated, substantially as described.

Signed at New York, in the county of New

York and State of New York, this 30th day of January, A. D. 1901.

WALTER SCOTT.
